UNITED STATES PATENT OFFICE.

LEANDER W. HAMMOND, OF NORTH PLAINFIELD, NEW JERSEY, ASSIGNOR
OF ONE-HALF TO FAY N. LONGWELL, OF NORTH PLAINFIELD, NEW
JERSEY.

TROUSERS.

SPECIFICATION forming part of Letters Patent No. 738,677, dated September 8, 1903.

Application filed June 6, 1903. Serial No. 160,388. (No model.)

To all whom it may concern:

Be it known that I, LEANDER W. HAMMOND, a citizen of the United States, residing at North Plainfield, in the county of Somerset and State of New Jersey, have invented new and useful Improvements in Trousers, of which the following is a specification.

My invention relates to trousers; and the object of the same is to construct a trousers-leg in such a manner that it will yield and draw up when one sits down and not stick to the calves of the legs and stretch and bag at the knees.

The simple and novel construction employed by me in carrying out my invention is fully described and claimed in this specification and illustrated in the accompanying drawings, forming a part thereof, in which—

Figure 1 is a side view of a trousers-leg on a bended leg. Fig. 2 is an elevation of a trousers-leg with my invention thereon. Fig. 3 is a detail of the knee-lining. Fig. 4 is a detail of bottom lining. Fig. 5 is a rear elevation of a trousers-leg turned inside out. Fig. 6 is a section on the line 6 6, Fig. 2. Fig. 7 is a section on the line 7 7, Fig. 2.

The numeral 1 designates a trousers-leg formed of a front breadth 2 and a rear breadth 3, united at the edges by seams 4. Located just opposite the knee portion of the trousers-leg 1 is an antifriction-lining 5 of haircloth or satin, which extends from seam to seam of the leg 1 and has a notch 6, formed in the upper edge thereof, which has straight downwardly-inclined sides 7, running from the seams 4 to the center of the front breadth 2. The bottom 8 may also be notched, but I have shown it cut square. The notch 6 enables the leg to conform more nearly to the shape of the knee and prevents drawing and wrinkling of the lining 5.

Mounted in the back of the leg 1 and extending from the bottom 1^a to about eight inches or a foot upwardly is an antifriction-lining 9, firmly secured at its edges to the rear breadth 3 and having a notch 10 in the top thereof similar to the notch 6.

Both legs 1 of a pair of trousers are supplied with the knee and bottom linings 5 and 9. When sitting down with a pair of trousers on provided with antifriction-linings 5 and 9, the rear of the bottoms of the legs will draw in against the calves of the legs, as is usual, but the lining 9 will not stick to the calf, but will yield and permit the bottom of the trousers-leg 1 to draw up and make room for the knee. The lining 5 will also yield and assist in the operation. The notches 6 and 10 enable the upper edges of the linings 5 and 9 to pull straight and not pucker, thereby assisting in the operation.

I do not wish to be limited as to details of construction, as these may be modified in many particulars without departing from the spirit of my invention.

Having thus described my invention, what I claim as new, and desire to secure by Letters Patent, is—

1. The combination with a trousers-leg of an antifriction-lining mounted within the knee portion of said leg and firmly secured in the front portion thereof, and an antifriction-lining mounted within the rear bottom portion of said leg and firmly secured thereto, said linings being designed to permit the trousers-leg to yield and draw up when the wearer bends his knee, substantially as described.

2. The combination with a trousers-leg, of an antifriction-lining located within the knee portion of said trousers-leg and having a notch formed in the upper edge thereof, the sides of which notch extend from the side seams of the leg to the center of the front breadth thereof, and an antifriction-lining located within the rear of the bottom portion of said leg and firmly secured thereto, substantially as described.

In testimony whereof I have hereunto set my hand in presence of two subscribing witnesses.

LEANDER W. HAMMOND.
